UNITED STATES PATENT OFFICE.

SAMUEL M. HERBER, OF INZA, MISSOURI.

LIME RECLAMATION FROM OIL-DISTILLATION RESIDUUM.

1,183,458.

Specification of Letters Patent. Patented May 16, 1916.

Application filed December 8, 1915. Serial No. 65,736.

To all whom it may concern:

Be it known that I, SAMUEL M. HERBER, a citizen of the United States, residing at Inza, in the county of Buchanan and State 5 of Missouri, have invented certain new and useful Improvements in Lime Reclamation from Oil-Distillation Residuum; and I do hereby declare the following to be a full, clear, and exact description of the invention, 10 such as will enable others skilled in the art to which it appertains to make and use the same.

My invention relates to furnaces and more particularly to a special form of furnace designed primarily for the reclamation of lime after the latter has been employed in the process of oil distillation and consequently intermixed with carbon and the heavier oils incident to carrying out my distillation process, which latter has been duly 20 described and claimed in the Letters Patent granted to me.

The main object, therefore, of my invention, among others, is to provide means for 25 completely freeing the lime from carbon, heavier oils, etc., and my invention, with this object in view consists of certain novel features of combination and construction of parts which will be hereinafter clearly 30 set forth in the following specification, illustrated in the accompanying drawings and pointed out in the claims.

Other objects and advantages of my invention will be hereinafter made clearly 35 apparent.

Reference being had to the accompanying drawings, which are made a part of this application, in which,

Figure 1 shows a vertical sectional view 40 of my improved furnace, located to coöperate with any form of retort employed for the distillation of oil, and other purposes. Fig. 2 is a similar view showing the air conveyer pipes in section, and means em- 45 ployed in connection therewith, for the delivery of the air at any desired point in the combustion chamber. Fig. 3 is a top plan view, while Fig. 4 is a sectional view of Fig. 1 taken slightly above the upper surface of 50 the grate bars.

For convenience of reference to the various details of my invention and coöoperating accessories, numerals will be employed, the same numeral being used to designate a 55 similar part throughout the views.

Briefly stated, my invention consists in

providing a suitable form of furnace de- 60 signed primarily, as stated, for the reclamation of lime after it has been used in the distillation of oil and means for introducing air at the changing point of combustion, as will be necessary as the mass of combustible material is increased or diminished.

Referring in detail to the various features 65 of my invention and parts necessary to co- operate therewith, 1 designates the furnace walls made of any suitable material and erected upon a proper form of base or support and provided with any preferred form of grates 2 having suitable controlling lever 70 3 therefor, whereby the grates or any section thereof may be readily shaken to discharge the accumulated lime thereupon.

Extending into the combustion chamber 75 4 thus or otherwise provided, I prefer to provide the pipe sections or tubular mem- 80 bers 5, each having a plurality of air dis- charging ducts or slotted apertures 6 extending from near the top thereof to their bottom ends, which latter are designed to 85 rest directly and securely upon one of the cross bars or equivalent device, it being understood that there may be any preferred number of the pipes or tubular members 5 as may be indicated as desirable to produce 90 the best results. Obviously the tubular sections 5 may be round or square in cross section, though I have shown the same of the latter form, and designed to move longitudinally within each of the tubular sec- 95 tions 5, I provide the plungers or closures 8, one for each tubular section 6, and all preferably connected together as by suitable frame work 9 whereby all may be simultaneously raised or lowered by any 100 suitable means, as by the connecting chains 10, pulleys 11 and controlling cable 12 or other suitable means. The lower ends of the tubular members 5 are placed directly in communication with the air supplying 105 pipes 13 and inasmuch as the slotted apertures 6 are provided throughout the length of the tubular members 5, it follows that by raising or lowering the closure members or plungers 8, the said ducts or slotted open- 110 ings 6 may be wholly closed or any number thereof may be left open for the admission of air from the pipes 13 as will be clearly apparent.

It will be understood that the pipe sec- 110 tions 13 may be placed in connection with any suitable form of blower or fan whereby

the requisite degree of draft may be afforded to insure perfect combustion. In order to provide convenient means whereby the fuel may be readily supplied to the combustion chamber, I provide the opening 14 in the upper part of the furnace 1 and over said opening, I locate the conveyer chute 15, and mounted within said conveyer chute, I provide an endless carrier consisting of suitable sprocket chains or equivalent 16, passing over suitable pulleys upon the axle 17, the said chain being provided with a plurality of transversely disposed cleats or bars 18 and it is obvious that the said endless carrier will convey any material placed thereon and deliver the same into the opening 14, which latter may be easily closed or opened by means of the controlling lever 19 pivoted at the fulcrum point 20 and properly connected with the sliding cover 21 as will be readily apparent. In like manner, I have provided beneath the furnace a similar endless carrier, the parts of which are designated by the same numerals employed in the description of the delivery chute 15, and as a similar chute or trough-like member 22 is provided beneath the furnace, it is obvious that when the lime which has been freed of carbon, oil or the like, is deposited within the chamber 23 by an agitation of the grate bars 24 through the mediation of the controlling levers 25, it follows that the reclaimed lime will be delivered into the chute 22 and thence carried to any point desired by the endless carrier located therein.

While, primarily, my object is the reclamation of the lime, as stated, yet incidentally I also produce a high degree of heat which I am enabled to effectively employ in carrying out my oil distillation process, as by delivering the products of combustion, including any unconsumed gases, directly into the fire box of my retort, it being understood that the perforated gas pipe or burner 26 may also be provided in the pipe box and supplied with any suitable source of gas, thereby insuring the complete combustion of any gases that may be delivered from my improved furnace, as will be obviously necessary.

It will furthermore be readily apparent that my improved furnace may be operationally connected to or placed in coöperation with any preferred number of retorts, whereby the heat from my furnace may thus be efficiently employed to carry on the distillation process, incidentally producing a continuous supply of fuel employed for my furnace and consequently rendering the operation of reclaiming the lime as an intimate co-acting part of the distillation process, inasmuch as the fuel supplied by my retort when used in my furnace, will produce the requisite degree of heat required for the perfect operation of the retort, thus establish-

ing a substantial interdependence of the process of reclaiming the lime, and the process of oil distillation, wherein lime is used in connection with the oil.

Inasmuch as a relatively large quantity of lime is employed in my oil distillation process, it becomes very important and desirable that such lime be reclaimed in order that it may be used over and over again, and it will be clearly apparent that owing to the high degree of heat which I am enabled to produce within my furnace, the carbon and heavier particles of oil remaining in the lime will be completely released by the assured perfection of combustion incident to the supply of air at the combustion point, thereby permitting the free or recovered lime to drop downward upon the grate bars wholly free from impurities and ready for reissue. It is also obvious that since the free lime will drop down upon the grate bars in a compact mass, it would be impossible to introduce the requisite quantity of air to the combustion point, were it not for the means, which I have illustrated, comprising the tubular members 5 having a plurality of air delivering ducts or slots and means to tightly close all of said ducts at will above the combustion point, leaving only those ducts open which are still in the mass of flames, or at the combustion point.

It is obvious that further means may be employed for introducing air at the exact point of combustion and to change the air at a point to coincide with any change in the change of the position of the burning mass of material, and I, therefore, wish to comprehend and claim in this application, any suitable means whereby the introduction of air may be accomplished and the air delivered at any desired or changing point within the furnace.

Obviously as the quantity of reclaimed lime increases in the lower portion of my furnace, the combustion point for the mass of unfreed lime, mixed with carbon, oil and the like, delivered above the free lime will gradually rise higher and higher, thereby making it necessary to gradually raise the plungers or closures 8, so that the air exit point will be raised, as the quantity of burning material is increased; it being understood that the lower openings for the air become closed by the accumulation of reclaimed lime.

In the present application, I have shown but one retort placed in coöperation with my furnace, both being substantially on the same floor or level, but it will be understood that my improved furnace may be properly connected with any preferred number of retorts, or my form of furnace may be located directly below the retort in which case the products of combustion will

reach directly in contact with my retort and heat the same to the requisite degree.

Believing that the construction and manner of using my invention is thus made clearly apparent, further description is deemed unnecessary.

What I claim and desire to secure by Letters Patent is:

1. A furnace for the recovery of lime from carbon, oil and the like, comprising a suitable combustion chamber, grate bars, and means to operate said bars, and air supplying shafts having a plurality of perforations, supply pipes communicating with the lower ends thereof, and closures for said supply pipes adapted to be raised or lowered at will, and means to deliver the fuel supply throughout the upper portion of the furnace.
2. A furnace for the reclamation of lime from carbon, oil and the like, consisting of a combustion chamber, suitable grate bars therefor, in combination with air supplying shafts provided with a plurality of perforations or slotted openings on each side thereof, supply pipes for introducing air into the lower ends of said shafts, and means to open or close any preferred openings within said shaft whereby the air will be supplied directly to the burning mass of material within the combustion chamber without reference to the change of position of said burning mass.
3. A furnace for recovering lime from

carbon, oil and the like, consisting of a 35 furnace proper having a suitable combustion chamber and controllable grates therefor, of a plurality of air introducing pipes or shafts, each having a plurality of openings therein, means to introduce a supply 40 of air to the lower ends of said shafts, additional means to open or close any desired number of said openings whereby the point of introducing the air may be changed to compensate for any change in the point of 45 combustion and means to supply the desired quantity of fuel to the combustion chamber and to withdraw the recovered lime from the lower portion thereof.

4. A furnace for reclaiming lime from 50 carbon and the like, comprising a combustion chamber and means to introduce air at any desired point therein.

5. A furnace for recovering lime from 55 carbon, oil and the like and means to introduce air to any changed point of combustion.

6. A furnace for recovering lime from carbon, oil and the like, and means to introduce air under any desired pressure into 60 the bottom and at a plurality of points throughout the burning mass without reference to any change in the position of said burning mass.

In testimony whereof I have signed my 65 name to this specification.

SAMUEL M. HERRER
